UNITED STATES PATENT OFFICE.

JOHN INGHAM BURTT, OF PHILADELPHIA, PENNSYLVANIA.

DESIGN FOR A NAPKIN-RING BLANK.

SPECIFICATION forming part of Design No. 34,471, dated May 7, 1901.

Application filed April 2, 1901. Serial No. 54,093. Term of patent 7 years.

To all whom it may concern:

Be it known that I, JOHN INGHAM BURTT, residing in Philadelphia, in the county of Philadelphia, in the State of Pennsylvania, have invented and produced a new and useful Design for Napkin-Ring Blanks, of which the following is a specification, reference being had to the accompanying drawings, forming part thereof.

10 In the drawings,

Figure 1 is a plan view of a strip, showing my new design.

Figure 2 is a central longitudinal section of the same.

15 As shown in the drawing, the leading or material feature of my design consists of an oblong strip *a* of uniform width, terminating in fancifully shaped ends, and in which strip is formed a rectangular opening *b* midway of

its length. The respective ends of the strip 20 are shaped to the fanciful form illustrated, that is to say, each end presents in outline plan three scallops, *c*, *d*, and *e*, the central scallop *d* having greater longitudinal projection and breadth than the two side scallops *c e*.

Having thus described my invention, what I claim as new, and desire to secure by Letters Patent, is—

The design for a napkin ring blank, as 30 herein shown and described.

In testimony whereof I have hereunto signed my name to this specification in the presence of two subscribing witnesses.

JOHN INGHAM BURTT.
